*Primary Examiner—Brian N. Vinson
Attorney, Agent, or Firm—Longacre & White*[57] **CLAIM**

The ornamental design for a steering wheel security device, as shown and described.

DESCRIPTION

FIG. 1 is a front, left-side and top perspective view of a steering wheel security device, sized for application on trucks or other larger vehicles, showing our new design;

FIG. 2 is a front elevational view of the steering wheel security device shown in FIG. 1;

FIG. 3 is a rear elevational view of the steering wheel security device shown in FIG. 1;

FIG. 4 is a right-side elevational view of the steering wheel security device shown in FIG. 1;

FIG. 5 is a left-side elevational view of the steering wheel security device shown in FIG. 1;

FIG. 6 is a top plan view of the steering wheel security device shown in FIG. 1;

FIG. 7 is a bottom view of the steering wheel security device shown in FIG. 1; and,

FIG. 8 is a front, left-side and top perspective view of an alternate embodiment of the steering wheel security device of FIG. 1, the only difference residing in the length of the arm.

FIG. 1

FIG. 8

FIG. 2

FIG. 3

FIG. 4

FIG. 5

FIG. 6

FIG. 7
